REFRIGERATION EXPANSION VALVE AND
ADJUSTMENT MECHANISM THEREFOR

Earnest J. Dillman and Thomas E. Neakes, Detroit, Mich., assignors to Detroit Controls Corporation, Detroit, Mich., a corporation of Michigan

Application January 24, 1950, Serial No. 140,194

7 Claims. (Cl. 236—92)

1

This invention relates to new and useful improvements in refrigeration expansion valves and more particularly to adjustment mechanisms therefor.

One of the objects of this invention is to provide a refrigeration expansion valve of new and improved construction.

Another object is to provide a refrigeration expansion valve having a new and improved mechanism for adjustably varying certain of the operating characteristics of the valve.

Other objects will become apparent from time to time throughout the specification and claims as hereinafter related.

This invention comprises the new and improved construction and cooperative relation of parts which will be described more fully hereinafter and the novelty of which will be particularly pointed out and distinctly claimed.

In the accompanying drawings to be taken as part of this specification there are clearly and fully illustrated two preferred embodiments of this invention in which drawings—

Figure 1 is a view in longitudinal central section of a refrigeration expansion valve embodying one form of this invention.

Fig. 2 is a detail sectional view of the operating diaphragm and supporting spider for the valve shown in Fig. 1.

Fig. 3 is a detail view of the adjustment mechanism for the expansion valve shown in Fig. 1.

Fig. 4 is a detail end view of the adjustment mechanism shown in Fig. 3 taken on the section line 4—4 of Fig. 1 and with a portion broken away to show more clearly the construction.

Fig. 5 is a detail plan view on a reduced scale of the adjustment member shown in Figs. 3 and 4.

Fig. 6 is a view in longitudinal central section of another form of refrigeration expansion valve.

Figs. 7 and 8 show detail sectional views of the upper and lower diaphragms respectively of the valve shown in Fig. 6.

Figs. 9 and 10 are detail views of the adjustment mechanism for the valve shown in Fig. 6 and are similar to those disclosed in Figs. 3 and 4, Fig. 10 being taken on the section line 10—10 of Fig. 6 and broken away for clarity, and

Fig. 11 is a detail plan view of the adjustment member for the valve shown in Fig. 6.

Referring to the drawings by characters of reference and more particularly to Figs. 1 to 5 inclusive, there is shown a refrigeration expansion valve generally designated as 1 comprising a valve casing 2 having an inlet passage 3 and an outlet passage 4. The casing 2 has an enlarged end portion 5 opposite the inlet end and which encloses with a cover member 6 a pressure chamber generally designated as 7. There is a tubular projecting portion 8 which extends from the en-

2

larged end portion 5 of the valve casing into the pressure chamber 7. The valve inlet 3 extends through a tubular member 9 which is threadedly secured in a bore 10 in the valve casing 2 which is aligned with the bore of the tubular extension 8. Within the tubular member 9 there is provided a valve seat member 11. A spherical valve member 12 is positioned on the inlet side of the valve seat member 11 and is urged to engagement therewith by a spring 13 and a valve guiding member 14 which includes a polygonal guide plate. The valve member 12 is operated by a valve stem 15 which extends through the tubular projection 8 of the valve casing 2 and is guided in a tubular guide member 16 which is threadedly secured in the valve casing bore 10 and extends into the tubular projection 8. The valve stem 15 is packed against leakage through the guide member 16 as at 17, the packing being held in position by a spring 18 compressed by a threaded abutment member 19. The upper end wall 20 of the cover member 6 closing the end portion 5 of the casing 2 has a diaphragm 21 and operating spider 22 extending thereacross and enclosing a power element chamber 23. There is provided a dish-shaped plate member 24 having a central aperture 25 which engages the cover member end wall 20 at its periphery to hold the diaphragm 21 and spider 22 in position, the diaphragm 21 having its peripheral edge bent over the peripheral edge of the plate member 24 to secure itself and the spider 22 in position. A hermetic seal is accomplished by soldering the plate member and diaphragm to the cover 6 as at 26. Positioned against the underside of the diaphragm 21 and spider 22 and engaging the upper end of the valve stem 15 there is provided a thrust transmitting plate member 27 which is engaged by a spring 28 determining the operating force required for opening the valve and hence the superheat setting of the valve. A cylindrical member 29 is slidably positioned on the tubular casing extension 8 and has a cupped flange portion 30 receiving the lower end of the spring 28. The flange 30 of the spring supporting member 29 has two upturned ears 31 and 32 which are supported on the inclined surfaces of parallel upturned portions 33 and 34 respectively of an adjustment member 35. The adjustment member 35 is disc-shaped and has an elongated central aperture 36 providing a guide for longitudinal adjustment transversely to the valve casing extension 8. The member 35 has a downturned flange 37 at one end having an aperture or slot 38 receiving the projecting end of a threaded adjustment screw 39 extending through the side wall of the enlarged end portion 5 of the valve casing 2. The adjustment screw 39 extends through a threaded guide member 40.

The screw 39 is provided with packing as in-

dicated at 41 to prevent leakage of refrigerant from the valve, the end of the screw 39 being enclosed by a threaded cap member 42 closing the end of the bore in which the guide member 40 is secured. The pressure chamber 7 is communicable with the outlet passage 4 through a passage 43 providing an internal equalizer, although for some installations this passage might be eliminated and the chamber 7 connected by way of an external connection through the wall 5 or 6 and an external conduit to the outlet end of the refrigerant evaporator, this last-mentioned arrangement being commonly known as external equalization. Extending through an aperture in the upper wall 20 of the cover member 6 is one end of a capillary tube 44 which is soldered as at 45, the other end of which is connected to a responsive bulb element 46. The bulb element 46, tubing 44 and power element chamber 23 are charged with a quantity of volatile refrigerant to an extent known in the refrigeration art as a "liquid charge."

It should be noted that there are several distinct advantages obtained by the construction set forth herein whereby it is possible to construct individually a number of sub-assemblies which are eventually assembled into the complete valve thus providing a more efficient and less expensive construction and assembly. In the construction of this valve the valve inlet assembly comprising the tubular threaded inlet member 9, valve seat 11, valve member 12, valve guide 14 and closing spring 13 comprise a single unit which would be preassembled and threadedly connected in the bore 10 upon final assembly of the valve. This valve unit in addition to being the controlling valve for the flow of refrigerant also functions as a check valve since the valve member 12 is capable of having movement relative to and away from the operating stem 15. This check valve arrangement operates to prevent a reverse flow through the valve unless the pressure on the outlet side of the valve should exceed the pressure at the inlet by a predetermined amount determined by the scale of the closing spring 13, this condition being one which could practically never occur. The valve stem 15, guide 16, and its packing arrangement 17, 18, 19 would likewise be separately assembled and inserted as a unit in the bore 10 for transmission of movement from the operating diaphragm to the valve member 12. The power element assembly comprising the cover member 6, plate member 24, diaphragm 21, tubing 44, and bulb element 46 would also comprise a preassembled unit which would be installed directly on the end portion 5 of the valve body 2 and sealed thereon by peripheral soldering and an inturned casing flange portion as at 47. In this assembly the side wall of the casing cover portion 6 is rolled in around the periphery of the plate member 24 to hold it and the diaphragm 21 firmly against the casing end wall 20. It should be noted that by this construction there is provided a tight mechanical seal at the lower peripheral edge of the plate member 24 against which bears the rolled in side wall of the casing cover 6. There is also provided by this construction a camming or leverage action of the plate member 24 against the peripheral indentation or ridge 20 on the end wall 20 of the cover 6 which provides a second mechanical seal at that point. For purposes of this last-mentioned assembly the soldered connection at 41 would require a solder having a lower melting point than the solder connection

at 26 to prevent a melting of that connection during final soldering. The sleeve member 29 supporting the spring 28 is operable to have movement longitudinally of the tubular projection 8 to vary the compression of the spring 28 and thus vary the differential of pressure across the diaphragm 21 required to open the valve. By this adjustment the superheat setting of the valve may be varied. For adjustment of the spring supporting member 29 the inclined surfaces of the ears 33 and 34 on the adjustment member 35 are movable by the screw 39 under the inclined ears 31 and 32 of the supporting member 29. This adjustment provides an inclined plane or wedge action for spring adjustment. By this arrangement there is provided a simple mechanism for translating the longitudinal and rotary motion of the adjusting screw 39 into vertical movement of the supporting member 29 for spring adjustment.

In the form of the invention shown in Figs. 6 to 11 the wedge and spring adjustment member is shown as applied to an expansion valve of the "liquid charged" type having a pressure limiting arrangement. In this figure the valve is generally designated as 101 and comprises a valve casing or body 102 having an inlet 103 and an outlet 104. In the inlet 103 there is provided a tubular inlet member 105 which is threaded in the bore 106 which intersects the passageway extending to the outlet 104. In the member 105 there is a valve seat member 107 having cooperable therewith a spherical valve member 108 which is urged toward its seat by a spring 109 and polygonal guide member 110. The inlet 103 opens to the tubular member 105 through an inlet fitting member 111 which holds in position a strainer 112. The casing 102 has an enlarged end portion 113 which encloses an annular chamber 114 around a tubular casing projecting portion 115. The casing projecting portion 115 has a bore concentric with the bore 106 and aligned with the bore through the valve seat member 107. There is an operating valve stem 116 which engages the valve member 108 at one end and extends through the bore of the projecting casing portion 115. The valve stem 116 and surrounding projection is provided with packing as at 117 which packing is held in position by a spring 118 compressed by a packing nut 119. There is provided an internal aperture 120 in the casing 102 which provides for communication between the outlet passageway 104 and the annular chamber 114. Closing the upper end of the annular chamber 114 there is provided a diaphragm and supporting spider 121 and 122. The spider 121 and diaphragm are held in position by an annular dish-shaped member 123 which is secured at its periphery by an inturned casing flange portion 124 and hermetically sealed as by solder. A cup-shaped and cylindrical casing cover member 125 is positioned over the diaphragm 121 and is threadedly connected to the casing end portion 113 as at 126. The cover member 125 has positioned across its upper end a diaphragm and supporting spider 127 and 128 which is secured in position by an annular dish-shaped member 129 hermetically sealed as by solder indicated at 130. The plate member 129 is secured in position and the diaphragms 121, 127 and spiders 122, 128 are secured to their respective plate members as described for the valve shown in Fig. 1. The diaphragm operating spring 131 is positioned within the space enclosed by the upper diaphragm 127 and the cup-shaped cover member 125. Within the cover member 125 there is provided a thrust

transmitting structure interposed between the diaphragms 127 and 121 and which comprises upper and lower cup-shaped members 132 and 133, connecting bolt 134 and spring 135. The spring 135 holds the lower thrust transmitting member 133 against the head of the bolt 134 and is collapsible only upon occurrence of a predetermined pressure thereacross. The upper and lower thrust members 132 and 133 are positioned against thrust plates 136 and 137 respectively abutting the diaphragms 127 and 121. Opening into the space 128 enclosed by the cover 125 and the upper diaphragm 127 and soldered as at 139 is one end of a capillary tube 140, the other end of which has positioned thereon the responsive bulb element 141. For adjustment of the force required to open the valve there is provided a spring 142 in the annular chamber 114 abutting the thrust plate 143 on the diaphragm 121. The spring 142 is supported by a cylindrical adjustment member 144 having a spring supporting flange 145. The flange 145 of the tubular member 144 has a pair of upturned and inclined ears 146 and 147 which ride on the inclined surfaces of supporting ears 148 and 149 respectively of an adjustment member 150. The adjustment member 150 has a pair of dimpled portions 151 which provide a sliding contact with the lower wall of the annular chamber 114 for movement thereof. The member 150 has an elongated central aperture 152 which permits movement transverse to the casing projection 115 and has a downturned flange portion 153 into which fits an adjustment screw 154. The adjustment screw 154 extends through an aperture in the side wall of the casing and is provided with packing as at 155 and is held in position by a threaded bearing member 156. The end of the adjustment screw 154 is covered by a threaded cap member 157 closing the opening from which the adjustment screw extends.

In this form of valve the spring adjustment for variation of valve superheat setting is substantially the same as that described for the valve shown in Fig. 1. The turning of the adjustment screw in this arrangement causes the adjusting member 150 to be moved longitudinally of the screw thus varying the position of the inclined surfaces of the supporting ears 148 and 149 to provide an adjusting movement of the spring supporting member 144. The collapsible thrust member provided between two operating diaphragms permits the lower diaphragm 121 to be compressed toward the upper diaphragm at a predetermined maximum pressure in the valve, the lost motion between the diaphragms being taken up by the collapsible spring member. The power element bulb 141, tube 140 and power element space or chamber 138 would be filled with a "liquid charge" of refrigerant for temperature response. The collapsible spring arrangement 135 requires a predetermined collapsing force and thus provides the equivalent of a "gas charged" valve.

Having thus described the invention what is claimed and desired to be secured by Letters Patent of the United States is:

1. In a refrigeration expansion valve, a valve casing having inlet and outlet passageways, a valve member controlling flow of refrigerant through said passageways, an operating diaphragm in said casing arranged for actuation of said valve member, a spring opposing movement of said diaphragm in a valve opening direction, said casing having a guide projection extending toward said diaphragm, a supporting member for said spring slidably guided on and operable to

have sliding movement longitudinally of said guide projection, a wedge member arranged to have movement transversely to said guide projection and cooperable with said supporting member upon movement to vary the position thereof on said guide projection thereby to vary the compression of said spring, and means to adjust the position of said wedge member.

2. In a refrigeration expansion valve, a valve 10 casing having inlet and outlet passageways, a valve member controlling flow of refrigerant through said passageways, said casing having a portion defining a chamber communicable with refrigerant on the outlet side of the valve, a diaphragm closing said chamber and arranged for actuation of said valve member, means forming with said diaphragm a thermostatic power element for actuating said valve member, a spring opposing movement of said diaphragm in a valve opening direction, said casing having a tubular projection extending into said chamber, a supporting member for said spring slidably guided on and operable to have sliding movement longitudinally of said tubular projection, a wedge member in said chamber arranged to have movement transversely to said tubular projection and cooperable with said supporting member upon movement to vary the position thereof on said tubular projection thereby to vary the compression of said spring, and means to move said wedge member.

3. In a refrigeration expansion valve, a valve 30 casing having inlet and outlet passageways, a valve member controlling flow of refrigerant through said passageways, said casing having a portion defining a chamber communicable with refrigerant on the outlet side of the valve, a diaphragm closing said chamber and arranged for actuation of said valve member, means forming with said diaphragm a thermostatic power element for actuating said valve member, a spring opposing movement of said diaphragm in a valve opening direction, said casing having a tubular projection extending into said chamber, a supporting member for said spring, said supporting member being slidably guided on and operable to have sliding movement longitudinally of said tubular projection, a wedge member in said chamber arranged to have movement transversely to said tubular projection and underlying said supporting member and cooperable therewith upon movement to vary the position thereof on said tubular projection thereby to vary the compression of said spring, and a threaded adjustment member extending through a wall of said casing into said chamber and engageable with said wedge member for adjusting the position thereof.

4. In a refrigeration expansion valve, a valve 60 casing having inlet and outlet passageways, a valve member controlling flow of refrigerant through said passageways, said casing having a portion defining a chamber communicable with refrigerant on the outlet side of the valve, a diaphragm closing said chamber and arranged for actuation of said valve member, means forming with said diaphragm a thermostatic power element for actuating said valve member, a spring opposing movement of said diaphragm in a valve opening direction, said casing having a tubular projection extending into said chamber, a tubular supporting member guided for longitudinal movement on said projection and having a flange receiving and supporting one end of said spring, 70 said flange having a pair of inclined upturned

ears on opposite sides thereof, an adjustment member slidable along the lower end wall of said chamber transversely to said tubular projection, said adjustment member having a pair of upturned ears having inclined faces forming wedges cooperable one with each of said flange ears and operable upon said transverse movement to adjust the position of said supporting member on said tubular projection thereby to vary the compression of said spring, and means to move said adjustment member through said transverse movement.

5. In a refrigeration expansion valve, a valve casing having inlet and outlet passageways, a valve member controlling flow of refrigerant through said passageways, said casing having a portion defining a chamber communicable with refrigerant on the outlet side of the valve, a diaphragm closing said chamber and arranged for actuation of said valve member, means forming with said diaphragm a thermostatic power element for actuating said valve member, a spring opposing movement of said diaphragm in a valve opening direction, said casing having a tubular projection extending into said chamber, a tubular supporting member guided for longitudinal movement on said projection and having a flange receiving and supporting one end of said spring, said flange having a pair of inclined upturned ears on opposite sides thereof, an adjustment member slidable along the lower end wall of said chamber transversely to said tubular projection, said adjustment member having a pair of upturned ears having inclined faces forming wedges cooperable one with each of said flange ears and operable upon transverse movement to adjust the position of said supporting member on said tubular projection thereby to vary the compression of said spring, and a threaded adjustment member extending through a wall of said casing into said chamber and engageable with said adjustment member for moving said wedges relative to said flange ears.

6. In a refrigeration expansion valve, a valve casing having inlet and outlet passageways, a valve seat and port in said inlet passageway, a valve member cooperable with said seat to control flow through the valve, said casing having an enlarged end portion having an open-ended cylindrical cavity with a smooth end wall at one end, a thermostatic power element having a charge of volatile temperature responsive liquid therein and including a responsive bulb element, and a cover member and operating diaphragm closing the open end of said casing cavity, said casing having a tubular projection alined with said inlet passageway and valve port and extending from the end wall of said cavity into the chamber defined by said cavity, a valve stem guided within said projection and cooperable at one end with said valve member and at the other end with said operating diaphragm for transmitting movement to said valve member, a spring in said chamber surrounding said projection and cooperable with said diaphragm to resist movement thereof in a valve opening direction, a supporting member for said spring having a tubular portion guided on said tubular projection and having a flange receiving and supporting one end of said spring, said flange having a pair of upturned inclined ears on opposite sides thereof, an adjustment member having a flat base portion slidable along said cavity end wall and having an elongated central opening to permit movement transverse to said projection, said adjustment

5 member having a pair of upturned ears having inclined faces forming wedges registering one with each of the ears on said flange, said adjustment member being operable upon movement relative to said flange ears to vary the position of said supporting member on said tubular projection, and a threaded adjustment member extending through a wall of said casing into said chamber and engageable with said adjustment member for moving said wedges relative to said flange ears.

10 8. In a refrigeration expansion valve, a valve casing having inlet and outlet passageways, a valve seat and port in said inlet passageway, a valve member cooperable with said seat to control flow through the valve, said casing having an enlarged end portion having an open-ended cylindrical cavity with a smooth end wall at one end, a thermostatic power element having a charge of volatile temperature responsive liquid therein and including a responsive bulb element, and a cover member and operating diaphragm closing the open end of said casing cavity, an annular dish-shaped plate member securing the periphery of said diaphragm against said cover member and providing a stop limiting downward movement of said diaphragm to prevent rupture thereof by high pressures in the power element, said casing having a tubular projection alined with said inlet passageway and valve port and extending from the end wall of said cavity into the chamber defined by said cavity, a valve stem guided within said projection and cooperable at one end with said valve member and at the other end with said operating diaphragm for transmitting movement to said valve member, a spring in said chamber surrounding said projection and cooperable with said diaphragm to resist movement thereof in a valve opening direction, a supporting member for said spring having a tubular portion guided on said tubular projection and having a flange receiving and supporting one end of said spring, said flange having a pair of upturned inclined ears on opposite sides thereof, an adjustment member having a flat base portion slidable along said cavity end wall and having an elongated central opening to permit movement transverse to said projection, said adjustment member having a pair of upturned ears having inclined faces forming wedges registering one with each of the ears on said flange, said adjustment member being operable upon movement relative to said flange ears to vary the position of said supporting member on said tubular projection, and a threaded adjustment member extending through a wall of said casing into said chamber and engageable with said adjustment member for moving said wedges relative to said flange ears.
